[57] **CLAIM**

The ornamental design for a combined toothbrush and case, as shown and described.

DESCRIPTION

FIG. 1 is a perspective view of a combined toothbrush and case embodying my new design;

FIG. 2 is a side elevational view of one side thereof;

FIG. 3 is a side elevational view of the opposite side thereof;

FIG. 4 is a front elevational view thereof, the rear being a mirror image thereof;

FIG. 5 is a top plan view thereof;

FIG. 6 is a bottom plan view thereof; and,

FIG. 7 is an exploded perspective view thereof with the top portion of the case lifted from over the brush and neck portion of the toothbrush.

The undisclosed side of the toothbrush portion of the claimed design is the same in appearance as the side shown and the undisclosed rear of the toothbrush portion is unornamented.

FIG. 1

FIG. 2

FIG. 3

FIG. 4

FIG. 5
